UNITED STATES PATENT OFFICE.

JOHN W. BRASSINGTON, OF PORT ARTHUR, ONTARIO, CANADA, ASSIGNOR TO THE PAPER AND TEXTILE MACHINERY COMPANY, OF SANDUSKY, OHIO, A CORPORATION OF OHIO.

PAPER-MANUFACTURING MACHINE.

Application filed May 16, 1922, Serial No. 561,447. Renewed May 20, 1927.

This invention has relation to certain new and useful improvements in paper manufacturing machines and has particular reference to the class of paper manufacturing machines which gather the pulp from a vat onto a movable endless member operating around a suction roll immersed in the vat.

An object of the invention resides in the provision of a paper manufacturing machine in which the paper pulp is constantly agitated within the vat and gathered upon the movable endless member rotating with the cylinder of the suction roll while the water is drawn through the movable endless member into the cylinder of the suction roll and discharged at a suitable point outside of the vat.

Another object of the invention resides in the provision of a paper manufacturing machine of the character stated, in which the suction roll may be adjusted to vary the quantity of the pulp fibres drawn against the movable endless member, while provision is also made for varying the speed of rotation of the suction roll cylinder and travel of the movable endless member through the vat, thereby making it possible to regulate the quality and thickness of the sheets formed on the movable endless member.

A further object of the invention resides in the provision of a paper making machine of the character stated, in which the suction roll may be positioned above the agitating members within the vat and the suction roll adjusted or rotated a limited distance to properly position the suction surface thereof with respect to the agitating members and thereby vary the rate of attraction of the fibres from the paper making stock in the vat to the face of the movable endless member which may be in the form of a screen belt of fine mesh or a felt belt.

The invention has for a further object the provision of a paper making machine of the character stated in which the principles of the present invention may be incorporated in connection with suction rolls of various types.

A still further object resides in the provision of an improved construction and arrangement of gathering mechanism which may be especially adapted to the class of paper making machines in which the paper is made on the cylinder, which at present

gathers the fibres in such a manner from the quiet stock that the fibres all run in the direction of revolution of the cylinder, thereby producing a paper which is weaker in a transverse direction than its longitudinal direction. Such a machine having the elements of the present invention incorporated will operate to overcome this objection by agitating the stock and gathering the fibres upon the movable endless member of the improved mechanism with the fibres crossing one another and running in different directions, thereby producing a paper which is strong and durable and which will stand transverse strain as well as a longitudinal strain, owing to the crossing and interlocking of the fibres.

With the foregoing and other objects in view, as will appear as the description proceeds, the invention consists in the novel construction, combination and arrangement of co-operating elements as hereinafter more specifically set forth, claimed and shown in the accompanying drawings forming a part of the present application in which:

Figure 1 is a vertical section through the vat and parts carried therein constructed and arranged in accordance with the present invention.

Figure 2 is a side elevation of the vat and the parts carried thereby.

Figure 3 is a transverse vertical section, substantially on the plane of line 3—3 of Figure 1, looking in the direction indicated by the arrows.

Referring more in detail to the drawings in which similar reference characters designate corresponding parts throughout the several views, 3 indicates in general the vat of a conventional form of paper making machine, while 4 indicates the suction boxes, over which the movable endless member 5 travels with the paper pulp gathered from the vat 3. This vat 3 has near one side or end portion, the depending baffle plate 6 and the upstanding baffle plate 7 around which the stock must pass in entering the vat 3.

Positioned in the main portion of the vat 3 are the agitating members 8 which may be termed agitating fans and are carried upon shafts 9 extending upwardly through the bottom of the vat 3. The shafts 9 carry worm wheels 10 or the like on their lower ends and are engaged by driving worms or gears 11 on the driving shafts 12. It is

therefore evident that rotation of the shafts 9 will cause operation of the agitating members 8 which should be rigidly mounted thereon. A number of these agitating members 8 will serve to thoroughly agitate the stock within the vat 3 and to keep the fibres of the stock constantly in violent motion, moving in various directions in respect to one another within the vat 3.

10 The movable endless member 5 passes over suitable guide rollers 13 and one end of the movable endless member 5 passes around the rotatable cylinder 14 of the suction roll mounted transversely of the vat 3, 15 above the agitating members 8. The cylinder 14 should be perforated for at least the greater portion of its length and the movable endless member 5 is preferably constructed of a fine wire mesh. This suction 20 roll also includes a suction box 15 within the cylinder 14 and which should be held stationary during operation of the machine. The suction box 15 may be of the construction shown or of any other suitable and preferred construction but should be mounted so 25 that it may be adjusted or turned for a limited distance to properly position the suction surface thereof with respect to the agitating members 8. This adjustment may 30 be readily obtained by rotating the suction box by hand, or otherwise, to the required extent. The dotted lines in Figure 3 indicate such adjustment. The suction box is shown in the drawings as having an open 35 side 16 for the purpose of regulating the widths of the paper, as will be later understood. The suction box 15 has end members 17 rigid with the main portion (by welding or the like when formed separate from the main portion thereof, as shown in the drawing), and which end members 17 extend 40 through the end of the cylinder and form bearings upon which the cylinder 14 may rotate. The suction box ends 17 are mounted 45 in bearings 18 at the upper ends of the supporting members 19 positioned on opposite sides of the vat 3. Set screws 20 may be employed in the bearings 18 to secure the suction box ends 17 in position and prevent 50 rotation of the suction box 15 during operation of the machine. The adjusting screw 21 is rotatably mounted through the suction box ends 17, as shown in the drawings and may be controlled by a hand wheel 22 55 or the like on its extended end for adjusting the regulating member 23 of the suction roll and thereby regulating the width of the paper sheet produced by the machine. The member 23 is carried by a suitable support 60 24 within the cylinder 14 and connected with the rod 25. This rod 25 connects with the arm 26 projecting through the slot 16 of the suction box 15. The arm 26 has a sleeve 27 on its upper or inner end and is adapted 65 for movement on the threaded portion of

the adjusting screw 21 upon rotation of the latter. It is, therefore, evident that by proper operation of the screw 21, the member 23 may be moved longitudinally in the cylinder 14 to permit the formation of either a 70 wide or narrow sheet as may be desired. Longitudinal movement of the screw 21 is prevented by the annular collar 21^a thereof, working in the cap 21^b carried by the end member 17 through which the screw 21 is 75 extended.

Projecting from the cylindrical or main portion of the suction box 15 on either side of the open side 16, are the shoe guide walls 28 extending in parallel relation and carrying therein the shoes 29. The walls 28 should be of proper construction to permit shoes 29 to be carried therein in such a manner as to resiliently contact with the inner face of the cylinder 14. A suction 85 pipe 51 connects with one end of the suction box 15 and extends outwardly of the vat 3 for connection with suitable means, not shown, for causing a suction through the portions of the movable endless member 5 90 and the cylinder 14 opposite the slot 16 and outwardly through the suction pipe 51, thereby causing the agitated fibres in the vat 3 to be drawn against the outer face of the movable member 5 as the latter passes 95 through the vat 3. Attention may be called to the fact that a gear wheel 32 may be mounted on the cylinder 14, as shown in Figure 2, to provide for rotation of the cylinder 14 by suitable driving means, not 100 shown. The member 5, cylinder 14 and agitating members 8 are in constant motion during the operation of the machine. The sheet produced by gathering of the agitated fibres on the member 5, should be of uniform 105 thickness throughout its length and width. It is also evident that the suction box 15 may be mounted for limited rotation so that it may be turned to any position between that shown by full lines and the position indicated by dotted lines in Figure 3 for the 110 purpose of varying the position of the shoes 29 with respect to the agitating members 8 and thereby providing for a faster gathering and closer interlocking of the 115 fibres to produce the sheet on the member 5 when the suction box 15 is turned towards the agitating members. The result will be the reverse when the suction box 15 is turned at an angle to the agitating members. It 120 is therefore apparent that the character of the sheet produced may be varied as desired.

It is believed that the complete construction and operation may now be apparent 125 from the foregoing paragraphs taken in connection with the drawings without further detailed description. It may be briefly stated, however, that when the paper making machine is constructed in accordance with 130

this invention, the character of the product, as well as the width and thickness of the sheet, may be readily controlled by a simple adjustment of the parts and regulation of 5 rotation of the rotatable members, as previously mentioned.

While the preferred embodiment of the invention has been disclosed, it is to be understood that minor changes may be resorted 10 to within the scope of what is claimed without departing from the spirit of the invention.

What I claim as new is:

1. A paper making machine including a 15 vat, a movable endless member passing through said vat, means for constantly agitating the contents of the vat, means for causing an attraction of the fibres in the vat contents to one face of the movable endless member passing through said vat, the fibres being gathered in sheet form on said movable endless member, means for regulating the 20 quantity of fibres attracted to said movable endless member, and means within a suction roll in the vat to regulate the width of the sheet formed.

2. A paper making machine comprising a fibre containing vat, agitating members mounted for operation in said vat, a suction 30 roll mounted above said agitating members, said suction roll including an adjustable suction box adapted to be held in adjusted position during operation of the machine, a perforated cylinder surrounding said suction 35 box and adapted to rotate around the same during the operation of the machine and a movable endless member extending around said cylinder and adapted to move with the same, said suction box being constructed to 40 provide for a suction inwardly through said movable endless member and through said cylinder to attract the agitated fibres in the vat to the outer face of the said movable endless member in sheet form, said suction 45 box being adapted to be adjusted to regulate the quantity of fibres attracted to said movable endless member and the density of the fibres gathered thereon.

3. A paper making machine comprising a 50 fibre containing vat, agitating members mounted for operation in said vat, a suction roll mounted above said agitating members, said suction roll including an adjustable suction box adapted to be held in adjusted position during operation of the machine, a 55 perforated cylinder surrounding said suction box and adapted to rotate around the same during the operation of the machine, a movable endless member extending around said cylinder and adapted to move with the same, said suction box being constructed to 60 provide for a suction inwardly through said movable endless member and through said cylinder to attract the agitated fibres in the vat to the outer face of the said movable

endless member in sheet form, said suction box being adapted to be adjusted to regulate the quantity of fibres attracted to said movable endless member and the density of the fibres gathered thereon and means to 70 regulate the width of the sheet formed on said movable endless member.

4. A paper making machine including a vat, an endless fibre gathering member passing through said vat, means for agitating 75 fibres within said vat, a rotatable member partly enclosed by a portion of the endless member passing through the said vat and means extending through the rotatable member to provide for a suction through the endless member and a corresponding portion of the rotatable member to attract the agitated fibres to the outer surface of the said endless member passing through said vat and means within a suction roll in the vat for 80 regulating the width of the sheet formed.

5. A paper making machine including a fibre containing vat, a suction roll mounted in said vat, said suction roll including a cylinder and a suction box opening on a portion 90 of the face of said cylinder, fibre agitating members mounted for operation in said vat below the longitudinal centre of said suction roll and a gathering member operating around said cylinder to gather fibres from 95 the vat in sheet form, said agitating members serving to cause rapid movement of the fibres in various directions toward said suction roll, said suction roll being adapted to be adjusted to turn the suction box to various positions with respect to said agitating members for varying the quantity of fibres gathered on said gathering member.

6. A paper-making machine comprising, in combination, a rotating perforate cylinder; a stationary suction box coacting with the interior surface of said cylinder to provide a vacuum chamber at the lower side of the cylinder; a stock containing vat in which the portion of the cylinder traversing said suction-box is submerged; and an endless strainer medium passing around said cylinder on which a wet sheet is formed from said stock.

7. A paper-making machine having, in combination, a vat for the pulp solution; an endless strainer medium traveling into and out from the vat; a rotating perforate cylinder in the vat around which said member passes, the under side of which cylinder is 115 submerged in the solution in the vat; and a suction-box in said cylinder arranged to draw water of the solution through the traveling medium on a submerged area of the cylinder, thereby continuously gathering on the traveling medium a deposit of 120 pulp fibres in sheet form.

8. A paper-making machine having, in combination, a vat for the pulp solution; an endless strainer medium traveling into and 130

- out from the vat; a rotating perforate cylinder in the vat around which said member passes, the under side of which cylinder is submerged in the solution in the vat; a suction-box in the cylinder arranged to draw water of the solution through the traveling medium on a submerged area of the cylinder, thereby continuously gathering on the traveling medium a deposit of pulp fibres 5 in sheet form; and means beyond the cylinder traversed by the off-bearing run of said endless medium for subjecting said medium and pulp deposited thereon to suction action for removing water from the pulp 10 deposit.
9. A paper-making machine having, in combination, a vat for the pulp solution; an endless strainer medium traveling into and out from the vat; a rotating perforate cylinder in the vat around which said member passes, the under side of which cylinder is submerged in the solution in the vat; and a suction-box in said cylinder arranged to draw water of the solution through the 15 traveling medium on a submerged area of the cylinder, thereby continuously gathering on the traveling medium a deposit of pulp fibres in sheet form; said suction-box being angularly adjustable in the cylinder 20 and having means for securing it in different positions relative to the level of the pulp solution.
10. A paper-making machine comprising a vat and means embodying a suction-roll 25 for continuously gathering a deposit of pulp fibres in sheet form from the solution in the vat, said suction-roll having an angularly adjustable suction-box to permit shifting the suction area of the roll in relation to the level of the liquid in the vat. 40
11. A paper-making machine having, in combination, a vat for the pulp solution; an endless strainer medium traveling into and out from the vat; means operating in the vat for agitating the pulp solution; and means in the vat cooperating with said medium for gathering a deposit of pulp fibres in sheet form on said medium, said means adjustable to operate at different positions relative to said agitating means. 45
12. A paper-making machine having, in combination, a vat for the pulp solution; an endless strainer medium traveling into and out from the vat; means operating in the vat for agitating the pulp solution; and means comprising a suction-roll having a submerged suction area traversed by said medium for gathering thereon a deposit of pulp fibres in sheet form, said suction-roll constructed to permit adjusting its suction 50 area to different positions in relation to the agitating means. 55
13. A paper-making machine having, in combination, a vat; means for agitating the solution in the vat; and means embodying a suction-roll for gathering a deposit of fibres in sheet form from the agitated solution, said suction-roll having an angularly adjustable suction-box to permit varying the position of the suction area in the solution. 60

In testimony whereof I affix my signature.

JOHN W. BRASSINGTON.
